UNITED STATES PATENT OFFICE.

SVEN T. NELSON, OF CHICAGO, ILLINOIS, ASSIGNOR TO SULLIVAN MACHINERY COMPANY, OF BOSTON, MASSACHUSETTS, A CORPORATION OF MASSACHUSETTS.

VALVE.

1,299,762.

Specification of Letters Patent.

Patented Apr. 8, 1919.

Application filed April 8, 1915. Serial No. 20,077.

To all whom it may concern:

Be it known that I, SVEN T. NELSON, a citizen of the United States, and a resident of Chicago, in the county of Cook and State of Illinois, have invented an Improvement in Valves, of which the following description, in connection with the accompanying drawings, is a specification, like characters on the drawings representing like parts.

10 This invention relates to improvements in valves and more particularly to automatically acting intake and discharge valves for gaseous fluid compressors. The objects and features of the invention will best be understood from the following description, taken in connection with the accompanying drawings, of a portion of a compressor equipped with intake and discharge valves embodying one form of my invention and selected for 20 the purpose of illustration, it being understood that the invention in its true scope is definitely set forth by the claims.

Figure 1 is a central longitudinal section of a portion of a compressor provided with 25 intake and discharge valves embodying my invention;

Fig. 2 is a sectional view on line 2—2 of Fig. 1, looking toward the left;

Fig. 3 is a sectional view on line 3—3 of 30 Fig. 1, looking toward the right;

Fig. 4 is an elevation of the discharge valve;

Fig. 5 is an elevation of the intake valve;

Fig. 6 is an elevation of the discharge 35 valve viewed from the right hand side of Fig. 4;

Fig. 7 is an elevation of a guard or stop for the intake valve;

Fig. 8 is an elevation of the same viewed 40 from the right hand side of Fig. 7;

Fig. 9 is a modified form of discharge valve;

Fig. 10 is a modified form of intake valve.

Referring to Figs. 1 and 2 of the drawings, I have there shown a gaseous fluid compressor embodying one form of my invention selected for illustration, said compressor including a cylinder 2, within which a piston 4 works in the usual manner. The 50 cylinder head 6 is herein shown as comprising a main head 8 and a supplemental head 10, secured to the cylinder by a plurality of studs 12. This construction has been selected by reason of greater convenience of manufacture and assembly of the parts.

The supplemental head 10 is herein shown as chambered and partitioned to form an intake chamber 14 and a discharge chamber 16, the former communicating directly with an intake passage 18 through one or more ports 20, and the discharge chamber 16 communicating directly with a discharge passage 22 through one or more ports 24. Preferably, the supplemental cylinder head 10 will be provided with cover plates 26 and 28 for chambers 14 and 16, respectively, thus rendering the intake and discharge valves readily accessible for the purpose of inspection, without necessitating the removal of the entire head. Herein, the cover plate 26 is preferably secured in place by a series of screws 30, and the cover plate 28 by a series of screws 32.

The intake and discharge valves may be, and herein are, quite similar to each other, but they differ in certain respects, owing principally to the difference in requirements which necessitates variations in their valve seat and in their mounting.

As shown in Figs. 1 and 5, the intake valve includes a body 34, interposed between a valve seat 36 and a guard or stop 38, said guard or stop serving to limit the opening movement of the valve. In the form herein shown, the valve seat 36 is in the form of a plate of generally segmental shape, secured to the main head 8 by screws 40 passing through the margin of the valve and its guard and serving to secure both to the main head.

The valve body 34, as herein shown, consists of a relatively thin sheet of flexible and preferably elastic material, which in practice will be suitably tempered spring steel. This sheet or plate is herein provided with a marginal portion 42, perforated to receive the screws 40, and within its marginal portion the plate is provided with a plurality of slots (Fig. 5) indicated by the reference characters 44, 45, 46, 48, 50, 52, 54, 56, 58, 60, 62, 64 and forming tongues 66, 68, 70, 72, 74, 76, 78, 80, 82, 84, 86. Said tongues are connected at their free ends by a band 88, said tongues themselves thus constituting bands extending from said marginal portion 42 to said connecting band 88. In the intake valve, the marginal portion 42 extends all around the tongues or bands 66, 68, 70 . . . 86, but that portion of said marginal portion 42 which is adjacent the 110

connecting band 88 is separated from the latter by a slot 90, connected at either end to the slots 44 and 64, respectively.

The tongues or bands constitute elastic valves which overlie and normally close suitably formed apertures in the valve seat 36. If desired, there may be a plurality of apertures for each tongue or band, as hereinafter described in connection with the discharge valve; but for the purpose of illustrating two desirable forms of valve seats, the valve-seat 36 is herein shown as being provided with a plurality of apertures, 92, 94, 96, 98, 100, 101, 102, 104, 106, 108, and 110, generally corresponding with the tongues or bands of the valve body as to shape and location, though somewhat smaller than said tongues or bands in order that the marginal portions of the latter may normally rest against the valve-seat about the margins of said apertures.

It is to be noted that as the tongues or bands 66, 68, 70 . . . 86, are all connected at one end to the rectilinear part of the marginal portion 42 of the valve body and at their other ends to the connecting band 88, said tongues or bands will all buckle or flex together about said rectilinear portion of the marginal portion 42, that is to say, by joining the free ends of the tongues a single plate or valve is formed, having unbroken portions to cover the passages or openings in the valve seat and intermediate broken or removed portions, and adapted to buckle or flex as a whole about the rectilinear part of the marginal portion 42 of the valve body. The construction has this advantage, among others, that, the tongues or bands 66, 68, 70 . . . 86 being connected at both ends, there would be no loose or broken parts should any of said tongues or bands break. This might be of considerable importance, particularly in the case of large compressors.

The guard or stop 38, Fig. 7, may be and herein is identically outlined with the valve body and comprises a marginal portion 112 suitably perforated to receive the screws 40, and a plurality of slots 114, 116, 118, 120, 122, 124, 126, 128, 130, 132, 134, and 136, forming tongues or bands 138, 140, 142, 144, 146, 148, 150, 152, 154, 156 and 158, corresponding to the tongues or bands of the valve body just described and connected at their free ends by a connecting band 160, similar to the band 88 of the valve body, but such connection of the free ends of the tongues or bands of said guard is not essential.

The valve guard differs, however, from the valve body described, in that it is relatively thick and inflexible, in order that its tongues or bands may act as stops for the tongues or bands of the valve body. It is to be noted also that the tongues of the guard or stop are bent or curved out of the plane

of the marginal portion of the guard, in order to permit the necessary opening movement of the tongues or bands of the valve body. This construction is illustrated in detail in Fig. 7.

Owing to the described form and arrangement of the valve, a relatively large effective area of the intake is assured.

In order to provide for the passage of the gaseous fluid from the intake valve into the cylinder itself, the main head 8 is appropriately apertured, and preferably is provided with a multiplicity of small perforations 162, so that in case of breakage in the valve the pieces will not become lodged in the end of the cylinder and cause damage. The main head 8 is provided with a recess 164 into which the tongues or bands of the guard or stop 38 project, and if the free ends of said bands are connected by a connecting band, such as 160 above referred to, the main head will of course be provided with a correspondingly shaped recess to receive said band.

Referring now more particularly to Fig. 90, the discharge valve, in the form illustrated in said figure, consists preferably of a plate of relatively thin, flexible, and preferably elastic sheet material, which in practice, as in the case of the intake valve, is made of tempered spring steel. This plate is provided with slots 166, 168, 170, 172, 174, 176, 178, 180, 182 and 184, thus forming a plurality of tongues 186, 188, 190, 192, 194, 196, 198, 200, 202, 204, and 206, said tongues projecting from a marginal portion 208 and being joined together at their other ends by a connecting band 210. The marginal portion 208 is perforated to receive a plurality of screws 212. This valve body is herein interposed between a valve seat 214, constituting a part of the main head 8, and a stop or guard 216. The valve body and the guard are secured in place by the screws 212, in cooperation with a clamping bar 218.

The valve seat 214 is provided with appropriate apertures, which the tongues or bands 186, 188 . . . 206, overlie, and in this instance there is provided a plurality of perforations for each of said tongues or bands. This construction is preferred to that of the slots described in connection with the intake valve, for the reason that, where each valve port is made up of a number of small perforations, a better support is provided for the valve tongues or bands and there is less likelihood of breakage than where each tongue or band is supported only at its margin on the valve seat. In the construction shown there are several rows of such perforations, herein designated by the reference characters 220, 222, 224, 226, 228, 230, 232, 234, 236, 238, and 240, one series or row for each valve tongue.

It will be seen that in the case of the

discharge valve just described, as in the case of the intake valve previously described, the tongues or bands 186, 188 . . . 206 being connected to each other at both ends, said 5 tongues or bands will all buckle or flex together about the marginal portion 208, said tongues or bands constituting a single plate or valve that buckles or flexes as a whole.

Referring to Fig. 1, the stop or guard 216 10 for said discharge valve is identical in outline with the valve body itself, but is made of a relatively thicker and stiffer plate in order that it may possess the rigidity necessary to limit the opening movement of the 15 valve. This plate is herein provided with a plurality of slots 242, 244, 246, 248, 250, 252, 254, 256, 258, 260 (see Fig. 2). These slots form a plurality of tongues or bands 262, 264, 266, 268, 270, 272, 274, 276, 278, 280, and 282, 20 corresponding to the tongues or bands of the valve body and overlying them. These tongues or bands of the discharge valve guard 216 are curved or bowed outwardly from the plane of the guard body, like those 25 of the intake valve guard, to provide the space necessary for the opening movement of the discharge valve. Furthermore the degree of curvature of said tongues or bands of the discharge valve guard will correspond 30 to the degree of curvature of those of the intake valve guard. Referring more particularly to Fig. 2, it will be seen that herein the outer ends of the tongues or bands 262, 264 . . . 282 of the guard are joined together by a band 284, but this is not essential.

In Fig. 9 there is shown a modified construction of discharge valve, and in Fig. 10 a correspondingly modified construction of 40 intake valve. These valves are substantially the same as those already described, excepting that, as shown in said Figs. 9 and 10, a band extending transversely of the tongues connects the latter at a point intermediate 45 their ends. This construction is particularly advantageous where the valves are relatively large, thus necessitating tongues of considerable length. Owing to the flexibility of the material of which the valve body is 50 made, there might be danger, where the tongues are thus made relatively long, of said tongues becoming distorted or flexing irregularly, thus impairing the action of the valve. The band connecting the tongues at 55 a point intermediate their ends overcomes this difficulty by giving said tongues the necessary support, said connecting band having the effect of dividing the tongues into two series. As shown in said Figs. 9 and 10, 60 the intermediate connecting band described is designated by the reference character 286 in the case of the discharge valve and 288 in the case of the intake valve. When the modified construction shown in Figs. 9 and 65 10 is used, a stop or guard identical in out-

line with the valve body itself will preferably also be used. In Fig. 9, the two series of slots are represented by the reference characters 291 292, 293, 294, 295, 296, 297, 298, 299 and 300 forming the tongues or 70 bands 301, 302, 303, 304, 305, 306, 307, 308 and 309; and slots 310, 311, 312, 313, 314, 315, 316, 317, 318, 319, 320, 321, 322, 324 forming tongues 325, 326, 327, 328, 329, 330, 331, 332, 333, 334, 335, 336, 337 and 338. In 75 Fig. 10, the two series of slots are represented, the first by the reference characters 290' to 300', and the tongues formed thereby by the reference characters 300' to 309', and the second series of slots by the reference 80 characters 310' to 324', and tongues formed thereby by the reference characters 325' to 338'.

The mode of operation of the valves will be readily understood from the description 85 thereof given, and therefore no further explanation of the operation of the valves will be given, except to mention that when the piston travels toward the left (Fig. 1), the discharge valve will naturally remain seated, 90 while the intake valve will open, owing to the rarification of the gaseous fluid within the cylinder, and the relatively higher pressure of gaseous fluid in the intake chamber. On the other hand, when the piston 95 travels toward the right (Fig. 1), the intake valve will naturally be seated by the pressure of the gaseous fluid exerted thereagainst from within the piston chamber, and the compressed fluid will cause the discharge 100 valve to open and permit the fluid to flow from the cylinder chamber to the discharge chamber, and thence to the discharge passage, from whence it will pass to the usual 105 receiver.

While two specific embodiments of the invention have been described herein, it will be understood that the invention is not to be considered as limited to these embodiments or either of them, nor to the details 110 illustrated, but that said embodiments and details may be extensively and variously modified without departing from the true scope of the invention which is definitely set forth by the claims. 115

Claims:

1. As a new article of manufacture, a valve-body consisting of a plate of relatively thin elastic material, having marginal portions connected by unbroken portions separated 120 by intermediate broken out or removed portions, whereby when one edge of said plate is held fixed said plate will buckle or flex transversely.

2. In a valve for permitting the flow of 125 fluid in one direction and preventing its flow in the opposite direction, the combination of a valve-body consisting of a plate of relatively thin elastic material provided with marginal portions connected by unbroken 130

- portions separated by intermediate broken out or removed portions; a valve seat provided with apertures which said unbroken portions overlie and normally close; means to secure said plate in fixed relation to said valve seat along a single line, the construction and arrangement being such that said plate will buckle or flex as a whole about said line.
3. In a valve for permitting the flow of fluid in one direction but preventing its flow in the opposite direction, the combination of an elastic valve-body adapted to be flexed by the pressure of the fluid and provided with slots forming bands extending from a marginal portion and joined at their other ends and, being separated by said slots; a valve seat provided with apertures which said bands overlie and normally close; and a stop or guard similarly provided with slots forming bands joined at both ends to marginal portions and respectively overlying the bands of the valve-body, the latter being interposed between said seat and said stop.
4. In a valve for permitting the flow of fluid in one direction but preventing its flow in the opposite direction, the combination of an elastic valve-body adapted to be flexed by the pressure of the fluid and provided with slots forming bands extending from a marginal portion and joined at their other ends, said bands being separated by said slots and progressively decreasing in length from one point to another; a valve seat provided with apertures which said bands overlie and normally close; and a stop or guard similarly provided with slots forming bands joined at both ends to marginal portions and respectively overlying the bands of the valve-body, the latter being interposed between said seat and said stop.
5. In a valve for permitting the flow of fluid in one direction but preventing its flow in the opposite direction, the combination of an elastic valve-body adapted to be flexed by the pressure of the fluid and provided with slots forming bands extending from a marginal portion and joined at their other ends, said bands being separated by said slots; a valve seat provided with a plurality of series of perforations, one series for each band, which said bands overlie and normally close; and a stop or guard similarly provided with slots forming bands joined at both ends to marginal portions and respectively overlying the bands of the valve-body, the latter being interposed between said seat and said stop.
6. In a valve for permitting the flow of fluid in one direction but preventing its flow in the opposite direction, in combination, an elastic valve-body of generally segmental form adapted to be flexed by the pressure of the fluid and provided with slots forming bands extending from a marginal portion and joined at their other ends, said bands being separated by said slots; a valve seat provided with apertures which said bands overlie and normally close; and a stop or guard similarly provided with slots forming bands joined at both ends to marginal portions and respectively overlying the bands of the valve-body, the latter being interposed between said seat and said stop.
7. In a valve for permitting the flow of fluid in one direction but preventing its flow in the opposite direction, in combination, an elastic valve-body adapted to be flexed by the pressure of the fluid and provided with slots forming bands joined at their other ends, said bands being separated by said slots; a valve seat provided with apertures which said bands overlie and normally close; and a stop or guard similarly provided with slots forming bands joined at both ends to marginal portions and respectively overlying the bands of the valve-body, the latter being interposed between said seat and said stop.
8. In a valve for permitting the flow of fluid in one direction but preventing its flow in the opposite direction, in combination, an elastic valve-body having a marginal portion and provided with slots forming a series of elastic bands projecting from said marginal portion and joined at their other ends, said bands being entirely surrounded by said marginal portion and being adapted to be flexed by the pressure of the fluid; means for securing said marginal portion; a valve seat provided with apertures which said bands overlie and normally close; and means for limiting the opening movement of said valve-body bands.
9. As a new article of manufacture, a valve-body consisting of a relatively thin elastic plate of generally segmental form having a marginal portion and a plurality of bands connected at one end to said marginal portion and at the other end to a curvilinear connecting band.
10. As a new article of manufacture, a valve-body consisting of a relatively thin elastic plate of generally segmental form having a marginal portion and provided with a plurality of slots forming a group of bands entirely surrounded by said marginal portion and joined thereto and to a connecting band.
11. In a valve for permitting the flow of fluid in one direction but preventing its flow in the opposite direction, the combination of an elastic valve-body adapted to be flexed by the pressure of the fluid and provided with slots forming bands joined at both ends and separated by said slots, said bands progressively decreasing in length from one point to another; and a valve seat provided with

apertures which said bands overlie and normally close.

12. In a valve for permitting the flow of fluid in one direction but preventing its flow in the opposite direction, in combination, an elastic valve-body of generally segmental form adapted to be flexed by the pressure of the fluid and provided with slots forming bands extending from the marginal portion of said valve-body and connected at their other ends, said bands being separated by said slots; and a valve seat provided with apertures which said bands overlie and normally close.

13. In a valve for permitting the flow of fluid in one direction but preventing its flow in the opposite direction, in combination, an elastic valve-body having a marginal portion and provided with slots forming a series of elastic bands projecting from said marginal portion and connected at their other ends, said bands being adapted to be flexed in unison by the pressure of the fluid and being completely surrounded by said marginal portion; means for securing said marginal portion; and a valve seat provided with apertures which said bands overlie and normally close.

14. As a new article of manufacture, a valve-body consisting of a relatively thin elastic plate of generally segmental form having a plurality of bands projecting from said marginal portion and joined at their other ends.

15. As a new article of manufacture, a valve-body consisting of a relatively thin elastic plate of generally segmental form

having a marginal portion and provided with a plurality of slots extending transversely of said plate and forming bands projecting from said marginal portion and connected to cause them to move together in the operation of the valve.

16. As a new article of manufacture, a valve-body consisting of a relatively thin elastic plate of generally segmental form having a marginal portion and provided with a plurality of slots extending transversely of said plate and forming bands connected to cause them to move together in the operation of the valve.

17. As a new article of manufacture, a valve-body consisting of a relatively thin elastic plate having a marginal portion and provided with a plurality of slots extending transversely of said plate and forming bands projecting from said marginal portion and connected to cause them to move together in the operation of the valve.

18. As a new article of manufacture, a valve-body consisting of a relatively thin elastic plate having a marginal portion and provided with a plurality of slots extending transversely of said plate and forming bands connected to cause them to move together in the operation of the valve.

In testimony whereof, I have signed my name to this specification, in the presence of two subscribing witnesses.

SVEN T. NELSON.
